CLAIM

The ornamental design for a sanitary garment for animals, as shown and described.

DESCRIPTION

FIG. 1 is a side elevational view of a sanitary garment for animals showing my new design;
FIG. 2 is a top plan view thereof;
FIG. 3 is a top plan view of a second embodiment of FIG. 1;
FIG. 4 is a rear elevational view of FIGS. 1 and 3;
FIG. 5 is a side elevational view of FIGS. 1 and 3, the opposite side being a mirror image of the side shown;
FIG. 6 is a front elevational view of FIGS. 1 and 3; and,
FIG. 7 is a bottom plan view of FIGS. 1 and 3.

FIG. 1

FIG.2

FIG.3

FIG.4

FIG.6

FIG. 7
